CLAIM

We claim the ornamental design for main frame for MP3 player, as shown and described.

DESCRIPTION

FIG. 1 is a front, right and top perspective view of a frame for MP3 player showing my new design;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a front, right and top perspective view thereof, shown in its environmental use.

The broken lines are for illustrative purpose only and form no part of the claimed design.
